(57) CLAIM

An ornamental design for an optical transmitting and receiving apparatus, as shown and described.

DESCRIPTION

FIG. 1 is a Front view of the optical transmitting and receiving apparatus.

FIG. 2 is a Rear view thereof.

FIG. 3 is a Top Plan view thereof.

FIG. 4 is a Bottom view thereof.

FIG. 5 is a Right side view thereof, wherein the left side is a mirror image.

FIG. 6 is a Perspective view thereof.

FIG. 7 is a Perspective view showing a state that a lock mechanism is released; and,

FIG. 8 is a Perspective view thereof, wherein the broken line showing of the circuit board and cage are for illustrative purposes only and forms no part of the claimed design.
